UNITED STATES PATENT OFFICE.

ELLIS O. LONG, OF MANSFIELD, OHIO

DUMPING-WAGON.

No. 799,995.

Specification of Letters Patent.

Patented Sept. 19, 1905.

Application filed July 14, 1904. Serial No. 216,534.

To all whom it may concern:

Be it known that I, ELLIS O. LONG, a citizen of the United States of America, and a resident of Mansfield, in the county of Richland 5 and State of Ohio, have invented certain new and useful Improvements in Dumping-Wagons, of which the following is a specification.

My invention relates to that class of dumping-wagons which are adapted to dump the 10 contents of the wagon-box without the necessity of using a shovel or other device in removing the contents from the box.

The objects of my invention are, first, to afford facilities for dumping all of the 15 contents of the wagon at one time or in case it is desired to do so to afford means of dumping a part of the contents only.

A further object of my invention is to provide a means for reducing the force or pressure 20 of the load upon the slats when the operator is in the act of dumping the contents of the wagon-box.

Another object of my invention consists in the construction of a wagon-box having a series 25 of crank-shafts journaled in suitable bearings or braces provided on the sides of the box, upon which shafts are mounted and securely attached a series of hinged folding plates adapted to overlap each other, and a draw-bar composed of a series of double links 30 secured to the cranks of the shafts and means for imparting motion to all of the plates or slats simultaneously or separately at the option of the operator.

I attain these and other objects by the mechanism illustrated in the accompanying drawings, in which—

Figure 1 is a side elevation of my invention, showing the operating mechanism with 40 the slats or plates comprising the bottom of the box in open position. Fig. 2 is an end elevation. Fig. 3 is a side view of the double links, showing one of the links in closed position and the other link broken or in open 45 position. Fig. 4 is a detailed top view of one link, showing its construction, and a side and end view of the locking-knuckle. Fig. 5 is a side view of the front end of the box, showing an auxiliary end hinged to the upper portion, with a resilient catch or spring secured 50 to the end of the box and adapted to hold the auxiliary end at an incline with the body portion, as shown in dotted lines. Fig. 6 is a top view of the hinged folding slat or plate. Fig. 7 55 is a bottom view of Fig. 6, showing the method of hinging the plates to provide a means for

folding them and also showing the coil-springs having their ends engaging the movable and stationary portions of the plate. Fig. 8 is an end view of the hinged plate or slat, showing 60 it in folded position, and also the broken end of the crank-shaft.

Referring to the drawings, 1 indicates an ordinary wagon or box having its sides 2 flaring for the purpose of providing a means for 65 increasing the capacity of the box. In constructing the box I prefer to securely attach a series of braces 3 at intervals along each side thereof, the braces having their lower ends 5 turned up to provide hooked bearings, the 70 ends of the hooks extending above the level of the bottom of the box to close the bearings and prevent any danger of the shafts becoming disengaged therefrom. These braces are secured to the sides of the wagon-box in direct alinement with each other, and their number can be varied so as to provide for different sizes, widths, or dimensions of slats or plates, which will be described more particularly hereinafter. The upper ends 4 of the 75 braces conform to the contour of the flaring sides of the box to strengthen the latter.

A series of crank-shafts 6 are journaled in the opposite hooked bearings 5 and extend transversely across the box, the upturned 80 ends 7 of the crank-shafts being flattened and apertured, as at 8, for the reception of a pivot-pin or rivet 9. A draw-bar 10, composed of a series of double links 11, having suitable apertures in the ends thereof adapted 85 to receive the ends of the rivets 9, is adapted to connect the upper ends of the crank-shafts. The links 11 between their points of connection with the crank-shafts are pivotally connected together by means of the rivets 13, 90 the links being held in alinement by means of the locking-knuckle 12, consisting of a substantially U-shaped member, the arms of which fit over and embrace the adjacent ends 95 of the links at their pivotal point 13 to resist 100 and prevent the breaking of the levers or links in a downward direction. The free end 14 of the series of links forming the draw-bar is pivotally connected to the lever 15, which is an extension of that crank-shaft adjacent to the forward end of the box. One member 16 of the hinged folding plate is securely and rigidly fastened to the crank-shaft by the clamps 17 and is termed the "stationary" member. The remaining member 16^a 110 is connected to the member 16 by the hinges *a* and *b*, forming a complete plate or slat.

Two coil-springs 18 and 19 are securely attached to the bottom of the stationary member in such a manner as to leave ends 20 and 21 exerting a pressure against the bottom of the hinged member 16^a for automatically returning and maintaining it on a plane and in alinement with the stationary member 16 preparatory to closing the bottom after the contents of the box have been dumped. The complete plate comprising the members 16 and 16^a, is mounted upon each of the crank-shafts, leaving a margin of the hinged or folding member of the plate overlapping the next succeeding stationary member 16 for supporting it when the plates are closed, forming an imperforate bottom for the box. A space is left between the foremost plate and the front end of the box, the front plate having two resilient catches 22 attached to its forward edge and projecting therebeyond. An auxiliary end 23 is hinged to the upper portion of the end of the box and is adapted to swing loosely therefrom, the auxiliary end being normally retained at an incline, as shown in dotted lines 23^a, Fig. 5, with the body portion by the flat tension-springs 24, riveted to the end of the box. The auxiliary end when the box-bottom is closed is supported by the brackets or catches 22. A bracket 23^b is attached to the rear end of the box for the purpose of supporting the rear plate or slat when the bottom is closed. A notched segment 25 is secured to the side of the box, with which segment the lever 15 is adapted to mesh for securely locking the bottom in closed position. It will be noted that each complete slat or plate is mounted upon the crank-shaft a certain predetermined distance from the adjoining slat, so as to leave a margin of the movable member of each slat resting on and overlapping the stationary member of the next succeeding slat, which is securely attached to the crank-shafts for supporting the movable member and preventing it from dropping under the weight of the load. The cranks of the several shafts are in lateral alinement and disposed parallel with each other, their upper ends being connected together by means of the double-linked draw-bar, one end of which is secured to a lever, the draw-bar normally being horizontal, with the links in substantial alinement. When movement is imparted to the lever, it is communicated to the draw-bar and crank-shafts, upon which the plates or slats are mounted, giving them an oscillating motion with the inclination of the plates or slats toward the front end of the box, whereby the stationary members 16 are positively rotated to the inclined position, (shown in Fig. 1,) thereby withdrawing their support to the movable members 16^a, which drop to the position shown in Fig. 1 under the weight of the load. When force or pressure is exerted against the lever to operate the plates preparatory to dumping, the weight of the load on the hinged

folding part 16^a of the plates causes them to fold, as shown in Fig. 8, leaving an opening between the slats through which a portion of the contents is precipitated to the ground before the slats are fully opened, thereby decreasing the force or pressure necessary to dump the contents. The auxiliary end 23 of the box is released from the brackets which support it when the end slat is slightly oscillated by the lever, leaving an opening between the end of the box and the slat for relieving the pressure or end thrust of the contents, which has a tendency to work forward on account of the inclination of the slats. When it is desired to dump only a portion of the contents of the box, the links are broken by hand, releasing the locking-knuckle between the points of connection with the shafts, as shown in Fig. 3, by means of which each slat or plate may be operated separately and the contents carried or supported upon each slat or plate are dumped. The links are broken by exerting a slight pressure in an upward direction under the locking-knuckle. The knuckles support and lock the links at the point of their connection between the crank-shafts below the dead-center, thereby resisting the tendency of the links to break when it is desired to empty all of the contents of the box simultaneously.

Having fully described my invention, what I claim, and desire to secure by Letters Patent, is—

1. In a dumping-wagon, a series of crank-shafts journaled in the lower portion of the box, a linked draw-bar secured to the cranks of said shafts, an operating-lever made integral with one of the cranks, said links being broken between their points of connection with the crank-shafts, a locking-knuckle fitted to the draw-bar and adapted to lock the links at the points of their connection, means for oscillating said crank-shafts, substantially as and for the purpose described.

2. A dumping-wagon composed of a box having a series of crank-shafts journaled in the lower portion thereof, a linked draw-bar connected to the cranks of said shafts, a series of hinged slats adapted to fold rigidly secured thereto, springs secured to the under portion of the slats with the ends drawn out and adapted to automatically return the hinged part of the slat on a plane with the part secured to the crank-shaft, substantially as and for the purpose described.

3. In a dumping-wagon, a box composed of a series of crank-shafts journaled to the lower portion thereof, a linked draw-bar connected to said crank-shafts, a series of hinged folding slats rigidly secured to the crank-shafts, means for dumping a part of the contents before the slats are fully open, substantially as and for the purpose described.

4. The combination with a dumping-wagon, the bottom of which consists of a series of piv-

totally-supported plates, of a draw-bar composed of a series of links, a rigid crank-shaft to which each plate is secured, the crank-shafts each connected to the draw-bar at the opposite ends of each pair of links and means for operating the draw-bar.

5 5. The combination in a dumping-wagon having a bottom composed of a series of movable plates, successive plates from rear to front being capable of operation independently of the remainder for dumping a portion only of the load, of means connected with each of the plates for operating them simultaneously from one end of the wagon.

15 6. The combination with a dumping-wagon, the bottom of which consists of a plurality of sectional plates, of a linked or toggle-hinged draw-bar connected with the plates.

20 7. The combination with a wagon, the bottom of which consists of a plurality of sectional plates, and crank-shafts to which one section of each plate is secured, of a linked draw-bar, the ends of the links connected to the crank-shafts, the links being toggle-joined 25 at points intermediate their connections with the crank-shafts.

30 8. The combination with a wagon, the bottom of which consists of a series of sectional plates, crank-shafts to which one section of each plate is rigidly secured, the remaining section of each plate normally overlapping upon and being supported by the first-named section of the succeeding plate and means for actuating the plates.

35 9. In a dumping-wagon, the combination with a plurality of rocking dumping-plates, of a draw-bar formed of a plurality of pivotally-connected links, means connecting the plates and draw-bar, successive plates from rear to front capable of movement independently of the remaining plates, and means for operating the draw-bar and all plates simultaneously.

45 10. The combination with a dumping-wagon, of a bottom consisting of a plurality of pivotally-supported sections, movable sections hinge-connected to the pivoted sections, means for normally retaining the hinged sections in alinement with the pivoted sections 50 and means for operating the sections.

55 11. The combination with a wagon-body, of a bottom comprising a plurality of plates, a suitably-journalized crank-shaft for each plate, the plates secured to the crank-shafts, a draw-bar comprising a plurality of rigid sections, one end of each section being pivotally secured to a crank-shaft, the opposite ends of each section being pivotally secured together at a point intermediate each two crank-shafts 60 and means connected with the end section at one end of the draw-bar for operating the draw-bar.

65 12. A wagon-bottom consisting of rocking plates, each plate comprising two sections hinged together, one section being pivotally

mounted relatively to the body of the wagon, and means for rocking the pivotally-supported section, the remaining section automatically actuated and rocking immediately subsequent to the primary movement of the first section. 70

13. A wagon-bottom comprising a series of plates, each plate consisting of a pivotally-supported section and a second section loosely secured to the pivoted section, resilient means carried by the pivoted section for normally retaining the loose section in alinement therewith and means for positively actuating the pivoted section.

14. A wagon-bottom comprising a plurality of plates, each plate consisting of a pivotally-supported member and a second member loosely secured thereto, the members adapted to fold together, resilient means carried by one of the members and placed under tension by the folding of the members, and means for positively operating the pivoted member. 80

15. A wagon provided with a bottom comprising a series of pivoted plates, a draw-bar connected with the plates, the draw-bar consisting of a plurality of pivotally-connected 90 links and a knuckle embracing the links at their pivotal connections to prevent lateral movement of the links in one direction.

16. A wagon provided with a bottom comprising a series of pivoted plates, a draw-bar connected with the plates, the draw-bar consisting of a plurality of pivotally-connected links and a knuckle embracing the links at their pivotal connections to prevent lateral movement of the links in one direction, the 100 knuckle consisting of a U-shaped member engaging the links on three sides thereof.

17. The combination in a wagon-body, of a bottom composed of a series of movable plates, adapted to leave a space between one end of the bottom and the adjacent end of the wagon-body, and means for normally closing the space prior to the dumping of the wagon. 105

18. The combination in a wagon-bed, with a movable bottom having a space between one end thereof and the end of the bed, of movable means for normally closing the space prior to the dumping of the wagon, and for yielding under pressure from an endwise shift of the load when dumping. 110

19. The combination in a wagon-bed, with a bottom consisting of a plurality of movable plates, the end plate separated from the end of the bed, and an auxiliary end-gate pivotally connected to the bed and releasably engaging the end plate. 115

20. The combination with a wagon-bed provided with a bottom consisting of a plurality of movable plates, the end plate of which is separated from the end of the bed by a dumping-space and means for automatically closing this space prior to dumping. 125

21. The combination with a wagon-bed, the bottom of which is composed of a plurality of movable plates, the end plate of the series 130

separated from the end of the bed to form a dumping-space, of an auxiliary end-gate movably secured to the bed, and catches carried by the end plate for releasably engaging and holding the gate to close the space.

22. The combination with a wagon-bed, the bottom of which is composed of a plurality of movable plates, the end plates of the series separated from the end of the bed to form a dumping-space, of an auxiliary end-gate movably secured to the bed, catches mounted on the end plate for releasably engaging the end-gate to close the space and yielding means for normally moving the gate into engagement with the catches.

23. In a dumping-bed, the combination with a bottom composed of a series of folding slats, a series of crank-shafts on which the slats are mounted so as to leave the folding part of said slats resting on the next succeeding slat, springs secured to the under portion thereof adapted to retain the folding portions of the slats on a plane with each other after the contents of the box are dumped, means for simultaneously oscillating said slats whereby an opening is left between them, and means for independently operating said slats substantially as and for the purpose described.

24. A dumping-wagon, composed of a box having a series of crank-shafts journaled on the lower portion thereof, a double-linked draw-bar connected with the cranks of said shafts, a series of hinged folding plates secured to the shafts, and springs secured to the under portions of the slats, and means for

closing said slats simultaneously, substantially as and for the purpose described.

25. A dumping-wagon composed of a series of folding slats mounted on crank-shafts and adapted to overlap each other, a draw-bar 40 connecting said cranks together, a lever adapted to operate said cranks whereby an oscillating motion is imparted to the slats, an auxiliary gate hinged to the front end of said box and adapted to be maintained at an incline 45 with the body portion of said box, substantially as and for the purpose described.

26. The combination with a dumping-wagon provided with a series of rocking plates, of a draw-bar composed of a series of pivotally-connected toggle-links, means connecting the plates and linked draw-bar, and means for operating the draw-bar.

27. A dumping-wagon comprising a series of folding slats, pivotally-supported means to 55 which the slats are each secured, a double-linked draw-bar connecting the pivotally-supported means, and means for operating the draw-bar for dumping the slats simultaneously, the links of the draw-bar being capable 60 of folding from one end of the draw-bar to the other whereby the slats may be separately and successively dumped.

Signed at Mansfield, Ohio, this 27th day of June, 1904.
